EDWARD F. SHIPMAN, OF WOODHAVEN, NEW YORK.

FUSIBLE LINK OR STRUT.

1,302,234.

Specification of Letters Patent. Patented Apr. 29, 1919.

Application filed March 7, 1917. Serial No. 153,178.

To all whom it may concern:

Be it known that I, EDWARD F. SHIPMAN, a citizen of the United States, residing in Woodhaven, county of Queens, and State 5 of New York, have invented a certain new and useful Fusible Link or Strut, of which the following is a specification.

This invention is a fusible link, and is particularly adapted for use with automatic 10 fire sprinklers wherein it serves to normally maintain the valve of the sprinkler seated until such time as the temperature in the immediate vicinity of the sprinkler rises to a predetermined degree, whereupon the link 15 is disrupted under the influence of such temperature and allows the valve of the sprinkler to become unseated, thereby placing the sprinkler in operation.

The object of the invention is to provide 20 a link of the character specified which may be economically manufactured, is efficient in its operation of normally maintaining the sprinkler valve in its seated position, and is positively operable to allow of the operation 25 of the sprinkler under the influence of a predetermined degree of heat, even though said link become fouled by electrical wiring, or other adjacent obstacles.

More specific features of the invention, as 30 well as the operative and manufacturing advantages resulting therefrom, will be apparent from the following detailed description when read in conjunction with the accompanying drawings.

In the accompanying drawings, I have 35 illustrated different practical embodiments of the invention, but the constructions shown therein are to be understood as illustrative, only, and not as defining the limits of the 40 invention.

Figure 1 is a side elevation of an automatic sprinkler head, showing a fusible link, embodying the present invention, associated therewith.

Fig. 2 is a central, vertical, longitudinal section through said link, the plane of said section being indicated by the line 2—2 of Fig. 3.

Fig. 3 is a plan view of the link shown in 50 section in Fig. 2.

Fig. 4 is a vertical section taken substantially in the plane of the line 4—4 of Fig. 2, a certain strut member which I employ being shown in elevation.

Fig. 5 is a section in the plane of the line 55 5—5 of Fig. 3.

Fig. 6 is a perspective detail of said strut member detached.

Fig. 7 is a side elevation of a modified form of link embodying this invention. 60

Fig. 8 is a plan view thereof.

Fig. 9 is a perspective detail of the strut member used in the constructions of Figs. 7 and 8.

Fig. 10 is a section in the plane of the line 10—10 of Fig. 8, and

Fig. 11 is a perspective view of a second modified form of fusible link, also embodying the invention, which I may employ.

Referring to the drawings, A indicates 70 any well known form of sprinkler head provided with the usual valve a , and adjusting screw a' , to the upper end of which screw is fixed a deflector or spreader B, of any well known and conventional form. If desired, 75 however, adjusting screw a' may be actuated through the employment of a wrench or key, and the deflector or spreader fixedly mounted directly upon the portion of sprinkler head A through which screw a' is 80 threaded.

I have chosen, in showing the deflector or spreader B, to illustrate an improved and novel form invented by me, and on which I intend to file an application for U. S. Let- 85 ters Patent. This spreader embodies a substantially circular disk provided at its center with a hub b , whereby the same may be rigidly secured on the adjusting screw a' of the sprinkler head. The disk is provided 90 near its outer periphery with an annular depression or channel b' , which is corrugated radially. Apertures b^2 are provided in the disk adjacent the hub thereof, and further apertures b^3 are provided in the an- 95 nular channel b' , to allow of the upward spraying of water therethrough. Apertures b^3 further allow of the escape of any water that may become deposited in said channel. This improved spreader is very efficient in 100 operation, as the dispensation of water coming in contact therewith is accomplished in substantially every direction.

The preferred form of link of this invention is shown in Figs. 1 to 6, inclusive. It 105 embodies, in the main, two complementary levers C, with which is associated a strut member D. Levers C are each preferably formed from a sheet of phosphor-bronze, which is stamped up into the shape shown 110 in Figs. 2 and 3, whereby each lever C embodies a forward portion c , and a rearward

portion c' , which portions lie in substantially parallel planes, with an intermediate portion c^2 forming an off-set.

When properly assembled, with the portions c' of the two levers in face-abutting relation, with an intermediate layer of soft fusible solder e , the off-set portions c^2 will be in the diverging relation shown in Fig. 2, and between those parts of the levers where the off-set portions c^2 intersect the portions c , is inserted the strut D. The portions c are comparatively short, relative to the length of the levers C, and each of said portions is provided with a cupped depression c^3 , one of which fits over the apex of valve a , the other receiving the lower tapered end of adjusting screw a' . If the rear portions c' of the two levers are soldered together as described, and the link associated with the sprinkler head A, as shown in Fig. 1, it will be apparent that, as adjusting screw a' is screwed down tight, a leverage action will result, wherein is found the strut member D operating as a fulcrum for levers C, of which the portions c are the work arms and the remaining portions c' and c^2 the power arms. The solder e , as long as it remains intact, maintains the work arms c in extended positions, but, when said solder releases the power arms, the pressure of water behind valve a causes the work arms to be forced together and the power arms to part, the two levers C operating on fulcrums formed by the opposite ends of strut D.

In the drawings, several ways are shown for maintaining strut member D against inadvertent displacement during the assembling of the link, as well as during the subsequent operations thereof, and these different ways will be described in connection with the modified forms of the link with which they are used. However, in the construction of Figs. 1 to 6, this is accomplished by forming the lateral edges of each lever, during the stamping-up operation, with a pair of oppositely positioned sockets d , positioned in the vertical plane of strut D, and providing said strut with projections d' , which extend beyond the ends of the strut proper and seat in said sockets, as shown best in Figs. 3 and 4. By virtue of the engagement of the projections on the strut with the pockets of levers C, any slipping or dislodgment of the strut, while the parts are assembled, is absolutely precluded, and said strut remains in the position in which it is initially placed until the disruption of the link under the influence of heat.

Considerable difficulty is frequently encountered in the assembling of fusible link portions and the soldering of these portions in proper position, because of the necessity of obtaining accurate relation between the parts. I have found by experiment that this objection may be readily overcome by stamp-

ing up complementary projections and sockets, f and f' , respectively, in the portions c' of the levers, as shown best in Figs. 3 and 5. In carrying out this construction, each lever is formed in the same way and from the same die, being provided with two or more sockets and a corresponding number of projections so positioned that, when any two levers are taken from the die, reversed and placed in the face-abutting relation described, the projections of one will register with the sockets of the other, and vice versa. By this arrangement, the two levers C may be accurately and expeditiously positioned and soldered in proper relation by merely bringing the projections and sockets into register in an entirely mechanical way.

The link thus far described may be practically employed with high efficiency by simply flooding the free edges of portions c' with fusible solder, which, in conjunction with the intermediate layer of solder e , will serve, under ordinary conditions, to maintain valve a seated. However, to guard against excess strain and varying fluid pressure behind valve a , it is desirable to provide additional means for normally maintaining the work arms of the levers in abutting relation, thereby relieving the fusible solder from carrying the entire load.

This means is embodied in a locking member composed of two strips, h h' , of comparatively light but rigid material, the major portion of each of which strips is soldered to the outer face of portion c' of each lever C, the remainder of said strips being formed into jaw portions adapted to interlock, as shown best in Fig. 2. In order that the interlocked portions may not become bent or distorted, and thereby released from one another through the fouling of the link by some adjacent projection, said portions are preferably set into and housed within cut-out portions h^2 formed in the ends of the work arms of levers C. Strips h and h' thus serve as small, secondary locking levers for holding the work arms of the link together until, by the action of heat, the fusible solder which unites the parts becomes melted, whereupon said parts are released and the link is disrupted by hydraulic pressure. In the exterior faces of the lever portions c' and the adjacent faces of the strips h h' , are preferably formed complementary projecting and reentrant portions h^2 which serve to facilitate the assembling of said strips on the link in a manner to insure uniformity of this operation and obviate binding between the strips and levers.

It will be noted, with respect to the secondary locking strips, that they are so formed that the melting free of either will allow of the disruption of the link, even though the other strip remains secured to the link. In practice, all that portion of the

link rearward of the off-set portions c^2 is preferably flooded over with fusible solder, as indicated by the dotted line g , but, when subjected to the required temperature, this 5 solder readily fuses and the link operates, in the manner described, to set the sprinkler in operation.

In the modified construction of Figs. 7 to 10, inclusive, the two complementary levers 10 I are of the same general form as the levers C, and are provided with assembling projections i and sockets i' , corresponding to similar members f and f' of the preferred construction. The strut member J, while performing the same function as strut member 15 D, is maintained in operative position through the employment of different means, the same end being accomplished in the present case by bending up rearwardly extending fingers i^2 at the lateral edges of strut J. When the link is assembled, the ends of fingers i^2 will engage with the off-set portions 20 of levers I, while the intermediate end portions of said strut will engage with the exterior 25 walls of the cup-shaped depressions i^3 , which correspond to the like depressions c^3 , as clearly shown in Fig. 7. By this arrangement, movement of the strut longitudinally of the link or twisting of said strut is obviated.

Strut D is shown as provided with a stiffening rib d^2 , so that adequate strength may be had even though comparatively light material is employed. Such a stiffening rib or 35 corrugation may be employed in the modified form of strut J, as well as in the strut hereinafter to be described with the modified construction of Fig. 11, but, as said rib is not entirely essential, the same is omitted from 40 these latter showings.

In the construction of Figs. 7 to 10, modified locking means is employed in lieu of the locking strips h h' of the preferred construction. The formation of this modified 45 means consists in stamping out registering slots k from the edges of the abutting portions of the levers I, and flowing soft fusible solder into and about said cut-out portions in such manner that the fusible solder takes, 50 in effect, the form of rivets k' (see Figs. 8 and 10). Because of the amount of solder employed in the formation of these rivet-shaped members, any number of which may be employed, the integrity of the link may 55 be preserved against excess strains. In practice, all that portion of the link rearward of the off-set portions of the levers is preferably flooded over with solder, as designated by the dotted lines k^2 in Fig. 7.

60 In the modified construction of Fig. 11, each lever L is formed, where the off-set portion meets the work arm of the lever, with an interior channel l , in which channels seat the opposite ends of a square-ended strut N. 65 The engagement of the strut with the chan-

nels precludes the twisting of said strut or the movement thereof longitudinally of the link. The link, as shown in this figure, is provided with locking means identical with the locking means of Figs. 1 to 6, although 70 the assembling projections and sockets are omitted. The rear portion of the link is, of course, in practice, flooded with solder, but, in the interest of clearness, its showing is omitted in this view.

A salient feature of advantage inherent in the constructions of this invention is that the opposite ends of any of the strut members D, 75 J or N, serve as independent fulcrums for two off-set levers, either one of which levers 80 is, in effect, operable entirely independently of the other, in its oscillation on its fulcrum. Thus, if the link, when in place upon a sprinkler head, becomes fouled by a rigid pipe, electric light wire, or other immovable 85 adjacent member, in such manner as to preclude the operation of one of the levers, this fact will not in the least impair the operativeness of the other. For example, if stock is stacked adjacent the link in such manner 90 that a box top comes into engagement with the under face of the lower lever, it will be manifest that, upon the fusing of the solder, said lower lever will be unable to turn on its fulcrum, because it is precluded from doing 95 so by the rigid material engaging therewith. However, as soon as the solder is melted, this will not preclude the operation of the upper lever, so that the same is free to turn on its 100 fulcrum, embodied in the upper end of the strut, and release the sprinkler for operation.

This principle of allowing of the operation of the link even though one lever thereof may be precluded from its normal operation, is carried out with respect to the secondary 105 locking strips h h' . It will be noted that these strips are so interlocked that either one, when released by the solder, may be readily disengaged from the other, even though the latter is still rigidly held in place. These 110 locking strips, while not interfering with the proper operation of the link, greatly reinforce the same, since it will be noted that each strip constitutes, in effect, a lever fulcrumed adjacent its interlocking end at the 115 rear edge of the levers C, the relatively long sustaining arms of the levers being normally held in face-abutting relation to the outer faces of levers C by the fusible solder, which, because of the considerable leverage, is not 120 subjected to any great degree of tension. As heretofore stated, the rear portions of the links are preferably flooded over with solder, as shown by the dotted lines g and k^2 in Figs. 2 and 7, respectively. This is considered the best construction, but very practical results may be obtained by the more economical method of applying solder in built-up form along the edges of the portions 125 c' of levers C, as well as the similar portions 130

relative to levers I. When the locking strips *h* and *h'* are employed, they are soldered to the main link levers in the usual way, but the interlocking portions of said strips are 5 preferably flooded over with solder, so as to preclude the corrosion of, and the depositing of sediment or other foreign material within, the interlocked portions of said strips.

10 The precluding of corrosion in the operating joints of fusible links is an important consideration, as is well understood, and, to obviate this difficulty, the parts of the link are frequently formed from phosphor-bronze, generally cast into shape. Phosphor-bronze, moreover, does not lose its resiliency or bend, even when subjected to a long continued strain, and, for this reason, too, it is 15 preferably employed in the present link. By 20 the formation of the parts of the link as described, however, the link of this invention may be readily stamped up, thereby greatly expediting the manufacture of the link and, because of the identity of the two main 25 levers, resulting in a great saving in time and cost.

The forming of the link of two off-set levers, each of which operates on a different fulcrum, and the work arms of which levers 30 are soldered together in face-abutting relation, in a plane perpendicular to the plane in which force is applied to the work arms of said levers, provides a very strong and 35 positively operating construction. In many prior art links, the parts of the link to which solder is applied, in attaching them together, move apart when the solder is fused by a sliding movement. However, in the present link, sliding movement is not availed of, 40 but a direct parting movement. In such a construction, atmospheric pressure, manifestly, assists the solder in holding the parts together, so that the solder, which forms the most expensive part of the link, may be used 45 more sparingly than in links of the prior art type specified. Moreover, the coöperating sockets and projections *f* *f'* and *i* *i'*, hereinbefore described as particularly adapted to facilitate in the assembling of the link, have 50 the further function of spacing members, as it will clearly appear from Fig. 5 that, when the two main levers of the link are positioned together, with an intermediate layer of solder, these coöperating sockets and 55 projections will always space the two levers the same distance apart, so that the layers of solder between the levers of a plurality of links will be the same. Thus, one link will have no more solder between its parts than 60 any other link made from the same die, so that, when the resisting strength of one link is computed, all the other links formed from the same die will have substantially the same strength in the respect mentioned.

65 It will be manifest from the foregoing de-

scription that the present invention embodies many features of novelty, some of which are included in one form and some in others. It will be understood that many of these several features of advantage may be incorporated in any one link, to the exclusion of other of such advantages, as is apparent from Fig. 11, wherein the benefit of the offset levers, coöperating strut, and locking members, is included, to the exclusion of the 70 assembling projections and sockets. In like manner, different combinations of these elements, within reasonable limits, will be apparent, and the invention is, therefore, to be understood as not restricted to the specific 75 showing made, but is as broadly novel as is commensurate with the appended claims.

Having thus fully described the invention, what I claim as new and desire to secure by Letters Patent, is:

1. A fusible link for fire sprinklers embodying two levers of the first class pivoted on separate fulcrums, with the work arms of the levers spaced apart and in substantially parallel relation and the portions of the power arms thereof adjacent the fulcrums converging to bring the remaining portions of the power arms into face-abutting relation, and fusible solder uniting said face-abutting portions of the power arms. 95

2. A fusible link for fire sprinklers embodying two levers of the first class pivoted on separate fulcrums, with the work arms of the levers spaced apart and in substantially parallel relation and the portions of the power arms thereof adjacent the fulcrums converging to bring the remaining portions of the power arms into face-abutting relation, fusible solder uniting said face-abutting portions of the power arms, 100 and depressed seats in the outer faces of the work arms for receiving the operating parts of the sprinkler. 105

3. A fusible link for fire sprinklers embodying two levers of the first class pivoted on separate fulcrums, with the work arms of the levers spaced apart and in substantially parallel relation and the portions of the power arms thereof adjacent the fulcrums converging to bring the remaining portions 110 of the power arms into face-abutting relation, fusible solder uniting said face-abutting portions of the power arms, depressed seats in the outer faces of the work arms for engagement by the sprinkler, and complementary recesses and projections on the abutting portions of the levers for facilitating the assembling and soldering of the levers together. 115

4. A fusible link for fire sprinklers embodying two levers of the first class pivoted on separate fulcrums, with the work arms of the levers spaced apart and in substantially parallel relation and the portions of the power arms thereof adjacent the ful- 125

- crums converging to bring the remaining portions of the power arms into face-abutting relation, fusible solder uniting said face-abutting portions of the power arms, 5 depressed seats in the outer faces of the work arms for receiving the operating parts of the sprinkler, complementary recesses and projections on the abutting portions of the levers for facilitating the assembling and soldering of the levers together, and additional means coöoperating with said abutting portions for assisting in the normal maintenance of the same in face-abutting relation.
5. A fusible link for fire sprinklers embodying two levers of the first class pivoted on separate fulcrums, with the work arms of the levers spaced apart and in substantially parallel relation and the portions of the power arms thereof adjacent the fulcrums 10 converging to bring the remaining portions of the power arms into face-abutting relation, fusible solder uniting said face-abutting portions of the power arms, and means, disruptable at a predetermined temperature, 15 associated with the face-abutting portions of the levers for assisting in the normal maintenance thereof in assembled relation.
6. A fusible link for fire sprinklers embodying two levers of the first class, both of 20 which are identical in shape, said levers being pivotal about separate fulcrums, with the work arms of the levers spaced apart and in substantially parallel relation, and the portions of the power arms thereof adjacent 25 the fulcrums converging to bring the remaining portions of the power arms into face-abutting relation, and fusible solder uniting said face-abutting portions of the power arms.
- 30 7. A fusible link for fire sprinklers embodying two levers of the first class, both of which are identical in shape, a strut, the opposite ends of which form two separate fulcrums, about each of which one lever is pivotal, the work arms of the levers being normally spaced apart and in substantially parallel relation, and the portions of the power arms thereof adjacent the fulcrums converging to bring the remaining portions of the power arms into face-abutting relation, and fusible solder uniting said face-abutting portions of the power arms.
- 35 8. A fusible link for fire sprinklers embodying two levers of the first class, both of which are identical in shape, a strut, the opposite ends of which form two separate fulcrums, about each of which one lever is pivotal, the work arms of the levers being normally spaced apart and in substantially parallel relation, and the portions of the power arms thereof adjacent the fulcrums converging to bring the remaining portions of the power arms into face-abutting relation, and fusible solder uniting said face-abutting portions of the power arms, the opposite 40 ends of the strut and the adjacent portions of the levers being complementarily shaped to preclude inadvertent shifting of the strut when the parts are assembled.
9. A fusible link for fire sprinklers embodying two levers of the first class pivoted on separate fulcrums, with the work arms of the levers spaced apart and in substantially parallel relation and the portions of the power arms thereof adjacent the fulcrums 45 converging to bring the remaining portions of the power arms into face-abutting relation, fusible solder uniting said face-abutting portions of the power arms, and a pair of locking strips soldered, for portions of their lengths, to the outer faces of the abutting portions of said levers and interlocked with one another beyond the free ends of said portions, either of which interlocked portions is readily disengageable from the other when the solder which holds said strip in place is fused.
- 50 10. A fusible link for fire sprinklers embodying two levers of the first class, both of which are identical in shape, a strut, the opposite ends of which form two separate fulcrums, about each of which one lever is pivotal, the work arms of the levers being normally spaced apart and in substantially parallel relation, and the portions of the power arms thereof adjacent the fulcrums converging to bring the remaining portions of the power arms into face-abutting relation, fusible solder uniting the face-abutting portions of the power arms, and means for precluding inadvertent shifting of the strut when the parts are assembled.
- 55 11. A fusible link for fire sprinklers embodying a pair of levers of the first class, both of which are identical in shape, and which levers are pivotal about separate fulcrums, the work arms of the levers being spaced apart in parallel relation, and a portion of the power arms being in face-abutting relation, in combination with fusible solder for uniting the abutting portions of the levers, a pair of additional lever members for normally locking the face-abutting portions in assembled relation, and fusible solder for normally holding the locking lever 60 members in locking positions.
- 60 12. A fusible link for fire sprinklers embodying two levers of the first class, both of which are identical in shape, a strut, the opposite ends of which form two separate fulcrums, about each of which one lever is pivotal, the work arms of the levers being normally spaced apart and in substantially parallel relation, and the portions of the power arms thereof adjacent the fulcrums converging to bring the remaining portions of the power arms into face-abutting relation, fusible solder uniting said face-abutting portions of the power arms, a pair of additional lever members for normally lock- 65

ing the face-abutting portions in assembled relation, and fusible solder for normally holding the locking lever members in locking positions.

- 5 13. A fusible link for fire sprinklers embodying two levers of the first class, both of which are identical in shape, a strut, the opposite ends of which form two separate fulcrums, about each of which one lever is pivotal, the work arms of the levers being normally spaced apart and in substantially parallel relation, and the portions of the power arms thereof adjacent the fulcrums converging to bring the remaining portions of the 10 power arms into face-abutting relation, fusible solder uniting said face-abutting portions of the power arms, and a pair of additional levers of the first class pivotal about separate fulcrums on the main levers, with 15 the work arms of the locking levers interlocked and the power arms secured to the main levers by fusible solder for locking the parts of the link in assembled relation until the application of heat melts the fusible 20 solder.

14. A fusible link for fire sprinklers embodying two levers of the first class, both of which are identical in shape, a strut, the opposite ends of which form two separate 25 fulcrums, about each of which one lever is pivotal, the work arms of the levers being normally spaced apart and in substantially parallel relation, and the portions of the power arms thereof adjacent the fulcrums 30 converging to bring the remaining portions of the power arms into face-abutting relation, fusible solder uniting said face-abutting 35 portions of the power arms, a pair of additional levers of the first class pivotal about

separate fulcrums on the main levers, with 40 the work arms of the locking levers interlocked and the power arms secured to the main levers by fusible solder for locking the parts of the link in assembled relation until the application of heat melts the fusible solder, and complementary reentrant and projecting portions on adjacent parts of the link to facilitate the assembling thereof. 45

15. A fusible link for fire sprinklers embodying two levers of the first class, both of which are identical in shape, a strut, the opposite ends of which form two separate fulcrums, about each of which one lever is pivotal, the work arms of the levers being normally spaced apart and in substantially parallel relation, and the portions of the power arms thereof adjacent the fulcrums converging to bring the remaining portions of the power arms into face-abutting relation, fusible solder uniting said face-abutting 50 portions of the power arms, a pair of additional levers of the first class pivotal about separate fulcrums on the main levers, with the work arms of the locking levers interlocked and the power arms secured to the main 55 levers by fusible solder for locking the parts of the link in assembled relation until the application of heat melts the fusible solder, and complementary reentrant and projecting portions on the main and locking levers 60 for facilitating the positioning of the locking levers in proper cooperative relation to the main levers during the assembling operation.

In testimony whereof I have signed my 65 name to this specification.

EDWARD F. SHIPMAN.
